UNITED STATES PATENT OFFICE

ANTHONY C. McGINTY, OF LOS ANGELES, CALIFORNIA

TURBINE

Application filed March 12, 1930. Serial No. 435,222.

This invention relates to turbines, and has for an object the provision of a turbine construction which is an improvement over that disclosed in Patent No. 1,776,038, issued to me on September 16, 1930.

A more detailed object is the provision of a turbine in which particular attention has been paid to the arrangement of the vanes of the rotor, as well as the configuration of each vane, whereby a materially increased efficiency of operation is attained. In greater detail, this invention contemplates the construction of the vanes of a rotor turbine, in such a manner that the steam or other motive fluid injected into the turbine housing, is caused to exert rotational effort against the vanes of the rotor for an increased period of time, the purpose being to cause a given quantity of steam or the like, to form an increased amount of useful work.

A further object is to provide means in conjunction with the rotor vanes, for compensating for the tendency toward throwing the steam outwards by centrifugal force, and thus overcoming one of the inherent deficiencies of the conventional turbine design.

A further object is to provide means for excluding the motive fluid from the bearings wherein the rotor shaft is journaled.

A still further object is to provide a novel type of turbine construction which is exceedingly small and compact, and yet which is capable of developing a relatively great power and of turning the rotor at relatively high speed, the intention being to make the turbine particularly applicable for use in aviation service which demands the maximum horse power output for unit of weight.

The invention possesses other objects and advantageous features, some of which, with those enumerated, will be set forth in the following description of the invention's particular embodiment which is illustrated in the drawings accompanying and forming a part of the specification.

Referring to the drawings:

Figure 1 is a top plan view of a turbine embodying the principles of the present invention. Portions of the figure are broken away to reduce its size.

Figure 2 is a side elevation taken in the direction of the arrow 2 of Fig. 1, and with a portion of the housing broken away to better disclose the construction of the rotor.

Fig. 3 is a vertical, longitudinal sectional view taken upon the line 3—3 of Fig. 1, with the direction of view as indicated.

Fig. 4 is a vertical, transverse sectional view taken upon the line 4—4 of Fig. 2, with the direction of view as indicated.

Fig. 5 is a vertical, transverse sectional view taken upon the line 5—5 of Fig. 2, with the direction of view as indicated.

Fig. 6 is an end elevation with the direction of view indicated by the arrow 6 of Fig. 1.

Specifically describing a preferred embodiment of the invention, the turbine comprises an elongated tubular housing 11 suitably mounted upon a base 12 whereby the turbine may be rigidly secured to any suitable supporting structure. Adjacent each end of the housing 11, a head 13 is positioned, this preferably being in the form of a disc of suitable metal fitted nicely within the bore 14 of the housing 11. Each of the heads 13 carries an anti-friction bearing 16 through the expedient of which a rotor shaft 17 is journaled axially of the housing 11, this shaft extending preferably throughout the entire length of the housing 11 and beyond the after end 18 thereof. Inasmuch as the particular embodiment of the invention being described, has been designed primarily for aviation service, a propeller 19 is shown mounted upon the after end 18 of the shaft 17.

A cap 21 is removably secured to each end of the housing 11, to protect the anti-friction bearings 16 from dust and the like. However, inspection of the bearings 16 may easily

be effected as a result of the ready removability of the caps 21 which are preferably retained in position through the expedient of a bayonet joint 22 of well-known design.

5 A rotor 23 is carried by the shaft 17 between the two bearing heads 13; and inasmuch as live steam or other suitable motive fluid is to be directed against the vanes 24 of the rotor 23, I prefer to provide a plate 10 26 adjacent the inner face of each head 13, and mount thereon, a stuffing-box 27 through which the shaft 17 extends. Packing material 28 pressed tightly against the shaft 17 by means of glands 29 or their equivalent, thus serves to prevent the escape of steam 15 from the rotor chamber 31, into either of the bearings 16, with the result that these stuffing-boxes and associated parts prevent loss of energy as a result of leakage, and also prevent 20 the deterioration of the bearings 16 which would otherwise occur.

The vanes 24 of the rotor 23 are rigid with the shaft 17, and extend between opposed end plates 32 and 33. Instead of extending radially 25 from the shaft 17 however, the vanes 24 are disposed substantially tangentially thereupon, extending from the outer surface of the shaft substantially perpendicularly with respect to a radius drawn from the line at 30 which the vane intersects the periphery of the shaft, as best shown upon Fig. 4. Moreover, each vane 24 extends rearwards from that side of the shaft to which it is attached, with respect to the direction of rotation of 35 the rotor 23, with the result that each adjacent pair of vanes 24 cooperates to define a substantially wedge-shaped pocket 34, the apex of which is on the surface of the shaft and points in the direction of movement 40 thereof, during rotation of the rotor. These pockets serve to catch the steam or other motive fluid, and transmit the maximum amount of energy from the moving steam to the rotor to effect rotation thereof.

45 Each vane 24 includes a portion 36 which extends substantially straight and parallel with the axis of the shaft 17, and also a slightly spiralled portion 37 which extends from the end of the associated straight portion 36, 50 toward the after end of the housing 11. Consequently, the two ends of the spiral portion 37 of each vane 24, are offset from each other with respect to the axis of the shaft 17, the direction of this offsetting being such that the after end of each vane is considerably behind the forward end thereof, during rotation 55 of the rotor.

A relieved portion 38 is provided in the outer edge of each vane 24 adjacent the after 60 or trailing end 39 thereof, and the after end plate 33 is of slightly reduced diameter, so as to permit escape of steam from the after ends 39 of the vanes 24, into that portion 41 of the rotor chamber 31 which is between the after end plate 33 and the after packing plate

26. An outlet valve 42 communicates with the portion 41 of the rotor chamber, to permit the escape of exhausted steam.

As best shown upon Fig. 4, the straight portion 36 of each vane 24, is corrugated or fluted longitudinally thereof. These flutings 46 may extend into the spiral portions 37 of the vanes 24, or they may terminate at the intersection of the spiral portions 37, with their respective straight portions 36. I prefer to provide a supporting ring 47 connecting the vanes 24 at their outer edges at this point of intersection. On the trailing side of the spiral portion 37 of each vane 24, a plurality of deflectors 48 are arranged. These deflectors are 70 preferably substantially U-shaped in cross-sectional configuration, opening toward that end 49 of the housing with which the steam inlet 51 is associated. Moreover, each of the deflectors 48 is disposed in angularity with 75 the axis of the shaft 17, so that it extends upon the after surface of the associated vane 24, and inclines toward the shaft 17 and toward the trailing end 39 of the vane. The purpose of these deflectors 48, is to catch the steam that 80 is moving along the vanes toward the exhaust, and direct the steam toward the shaft 17, thus overcoming the tendency for the steam to be thrown outwards by centrifugal action. Consequently, a greater percentage of the 85 inherent energy of the steam is directed against the vanes 24 or the deflectors 48, with a consequent reduction in the percentage of this energy which is expended against the inner 90 surface of the rotor chamber 31.

The steam inlet 51 includes a manifold 52 which is provided with a suitable coupling 53 for attaching an inlet conduit thereto, whereby steam or other suitable fluid under pressure, may be supplied to the manifold 52. The manifold 52 is rigidly mounted upon the housing 11, by means of a short length of tubing 54 or its equivalent, welded or otherwise secured at one end to the housing 11 and at the other end to the manifold 52. A nozzle 56 leads from the manifold 52 and enters the housing 11 in position to direct fluid under pressure against the after sides of the vanes 24, substantially midway between the ends of the straight portions 36 thereof. Hence, the nozzle 56 enters the housing 11 at an angle with a radius thereof, drawn from the point of intersection of the nozzle and housing, as best shown upon Fig. 4.

When steam or other suitable motive fluid is supplied under pressure to the manifold 52, it flows therethrough, and is directed at considerable velocity owing to the design of the nozzle 56, against the after or trailing faces of the vanes 24 at the straight portions 36 thereof. Inasmuch as the steam or other fluid impinges against the vanes at a point offset from the center of the shaft 17, rotation of the rotor 23 is effected. The flutings 46 in the straight portions 36, have the ten- 125 130

dency to entrap the steam and thus develop a greater efficiency by converting a larger amount of the inherent energy thereof, into rotational energy. Moreover, as the steam leaves the straight portions 36 and moves along the spiral portions 37, the fact that the trailing ends 39 of the vanes are behind the leading ends thereof, will compensate partially for the rotary movement of the steam within the housing, and thus also serve to increase the overall efficiency of my improved turbine.

As stated hereinabove, the deflectors 48 tend to work the steam inwards toward the shaft 17, and thus tend to overcome the movement of the steam away from the shaft 17, by centrifugal action. Obviously, the rotation of the rotor 23 effects similar rotation of the propeller 19, or whatever mechanism is coupled to the outer end of the shaft 17 to be driven thereby.

Thus it may be seen that I have developed an exceedingly compact turbine capable of operating with a high degree of efficiency in converting the maximum amount of energy of the steam or other motive fluid, into mechanical energy. The compactness and lightness of this prime mover, results in its being particularly applicable to aviation service, inasmuch as it is capable of developing a relatively high horse power per unit of weight.

It is to be understood that the details of the invention as herein disclosed, are subject to alteration within the spirit or scope of the appended claims.

I claim:

1. A turbine comprising a housing, a rotor revoluble therein and comprising a shaft journalled axially of said housing, a plurality of vanes rigid with and extending along said shaft, means for directing fluid against said vanes adjacent one end of the rotor, and a plurality of deflectors arranged on each vane and inclining toward said shaft and toward the other end of the rotor to direct said fluid inwards towards the axis of revolution of said rotor.

2. A turbine comprising a housing, a rotor revoluble therein and comprising a shaft journalled axially of said housing, a plurality of vanes rigid with and extending along said shaft, the ends of each vane being offset from each other about the axis of said shaft, means for directing fluid against said vanes, and a plurality of deflectors arranged on each vane and inclining toward said shaft and toward that end of the vane which trails as the rotor turns to direct said fluid inwards toward the axis of revolution of said rotor.

3. A turbine comprising a housing, a rotor revoluble therein and comprising a shaft journalled axially of said housing, a plurality of vanes rigid with and extending along said shaft, the ends of each vane being offset from each other about the axis of said shaft, each

of said vanes being arranged substantially tangentially with respect to said shaft and extending rearwards therefrom with respect to the direction of rotation of said rotor, means for directing fluid against said vanes, and a plurality of deflectors arranged on each vane and inclining toward said shaft and toward that end of the vane which trails as the rotor turns to direct said fluid inwards toward the axis of revolution of said rotor.

In testimony whereof I have signed my name to this specification.

ANTHONY C. McGINTY.
